Primary Examiner — Ricky Pham*(74) Attorney, Agent, or Firm* — Fredrikson & Byron, P.A.(57) **CLAIM**

I claim the ornamental design for a handle, as shown and described.

DESCRIPTION

FIG. 1 is a perspective view of my new design for a handle; FIG. 2 is a front elevation view thereof; FIG. 3 is a rear elevation view thereof; FIG. 4 is a top plan view thereof; FIG. 5 is a right side view, the left side view being a mirror image thereof; and, FIG. 6 is a bottom plan view thereof. The broken lines shown in the drawings are for illustrative purposes only and form no part of the claimed design.
